UNITED STATES PATENT OFFICE.

CARL HAHLWEG, OF STETTIN, GERMANY.

REPEATING MECHANISM FOR WATCHES.

SPECIFICATION forming part of Letters Patent No. 593,274, dated November 9, 1897.

Application filed August 4, 1896. Serial No. 601,581. (No model.)

To all whom it may concern:

Be it known that I, CARL HAHLWEG, watchmaker, a citizen of the Kingdom of Prussia, and a resident of Stettin, in the Kingdom of 5 Prussia and German Empire, have invented certain new and useful Improvements in Repeaters for Watches, of which the following is a specification.

My invention relates to repeating mechanism, especially adapted for watches, to sound the hours and quarter-hours whenever it is desired to know the time without being able to see the hands upon the dial. Heretofore the constructions employed have been so complicated and made to consist of so many delicately-constructed operating parts that they have been very expensive to make and hard to keep in perfect running order.

My invention consists in certain novel constructions and combinations of parts insuring accuracy, simplicity, and effectiveness of construction, as will be hereinafter described with reference to the accompanying drawings, in which—

Figure 1 is a plan view of the repeating mechanism in the normal or unwound position; Fig. 2, a plan view thereof when in the second position when wound up and the winding-lever is in position ready to be released to strike the hour and quarter-hour. Fig. 3 is a detail view of the hammer. Fig. 4 is a detail view of the quarter-striking rack-lever. Fig. 5 is a similar view of the hour-striking rack-lever. Fig. 6 is a detail of a latch-lever adapted to be supported upon the hour-striking rack-lever; Fig. 7, an enlarged detail of part of the striking-regulator mechanism and a part of the hour-rack; Fig. 8, a plan view of the regulator for the striking mechanism; Fig. 9, a section on line $x-x$ of Fig. 8; Figs. 10 and 11, a detail in two positions of the adjustable disks of the fly-brake mechanism; Fig. 12, a plan, and Fig. 13 a side elevation, of the leaves of the fly-brake; and Fig. 14 a plan of the said brake-regulator when the leaves are free and movable.

The wheelwork $z z' z^2$, provided with a striking-regulator hereinafter to be described, is supported below the plate q , and the master-wheel z carries the pinion t , whose teeth gear with those of the hour-rack s . The hour-rack lever s is bowed in the arc of a circle and

has twenty teeth thereon and is centered upon a hub s^4 , pivotally fixed upon a pin c on the watch-plate, as shown in Figs. 1 and 2, and 55 also having a lever-arm s^2 , which projects through a slot in the watchcase and is used to wind up the striking mechanism when it is required for use. A strong spring p , fixed in p^2 , presses with its end p' against a projection s^3 of the rack-lever s^2 , whereby the repeating-work is driven, and said spring p has near its end a horizontal slit extending from p^3 to p^4 , through which the lever s^2 passes. The rack s , after having been wound up by 60 pushing to one side the lever-arm s^2 in its recoil caused by the spring p , engages the lifting-pieces $e e'$ and actuates the hammer and also actuates the wheelwork $z z' z^2$, which is governed in its speed and prevented from running down by means of a centrifugal brake or regulating mechanism hereinafter to be described, and whereby the intervals between the single strokes are properly extended and equalized.

Upon the elbow and pivotal part of the rack s is placed a flat double-armed lever b , provided with two circular holes $b' b^2$ and the screw-holes b^3 , Fig. 6, the hole b' receiving a screw c , fitted into the rack-lever s to fulcrum the lever b upon said rack-lever, and the hole b^2 adapted to receive a headed screw c' , fixed in the rack-lever s , which screw prevents said lever b from leaving the rack s by means of its head surmounting the lever. 80 The screw c' has a certain amount of play in the hole b^2 of the lever b , Fig. 6, so that the said lever b is enabled to make a slight or oscillating movement upon the fulcrum b' with reference to the rack s and screw c , as 85 indicated in Fig. 5 by dotted and full lines, respectively.

A check-lever d is pivotally fixed on the lever b by a screw d' in the screw-hole b^3 (shown in Fig. 6) and is provided at its forward end with a hook d^3 and with a spring portion d^2 to press upon a pin u , fixed to the rack-lever s at the rear, and the middle of the forward end d of the lever abuts on the screw c' , thus limiting its movement. The 100 check-lever d therefore partakes of the slight motion of the lever b by means of its pivot of rotation d' being affixed thereto, and the spring end d^3 thereof acts upon the lever b in

such a way as to cause the hook d^3 of the check-lever d to be pressed in the direction of the quarter-rack v and the arm b^1 of the lever b in the same direction toward the step-wheel or jumping cam h . In this position the check-lever d holds the quarter-rack v in check, as shown in Fig. 1.

The quarter-rack v turns on a pin v^3 and lies free upon the rack s at the same height 10 as the check-lever d . It possesses three pairs of teeth v^6 and three noses $v' v^4 v^5$, which, like the teeth of the hour-rack s , can lift the lifting-piece $e e'$, and thereby the hammer a , to strike the first, second, or third of the 15 quarter-hours. In the position of rest, Fig. 1, in which the quarter-rack v is held in check by the lever d , the nose v' of the rack ascends gently and commences to turn up to 20 make contact with and lie close to the lifting-piece $e e'$, so that the tooth e is moved by it out of reach of the teeth of both the hour and the quarter racks and so remains until the 25 repeating mechanism is fully wound up and the hook d^3 of the check-lever is released, thus allowing the lifting-pieces $e e'$ free play and to be acted upon by its spring e^3 . The 30 hammer a is pivotally journaled with its pins $a^2 a^3$ passing through the curved opening w of the frame-plate and projecting beyond said 35 plate, while the pin a^7 does not extend over said plate, so that the movement of the hammer-spring r , provided for the engagement of the hammer a , may not be interfered with. The counter-spring lever k actuates the hammer a by pressing upon the pin a^2 and insures a clear, pure tone by forcing back the hammer 40 out of contact with the gong after each stroke. The lifting-piece $e e'$ turns on the frame-plate on a pin e^2 and is actuated by the teeth of both 45 racks, which engage with the tooth-like-shaped end e , and the free arm e' actuates the hammer a by catching the pin a^3 , projecting from the frame-plate. The tooth e is of such thickness that it can gear with the teeth of both racks 50 s and v . The arm e' , however, is thinner than said tooth e , so that the spring e^3 prevents the lifting-piece from being lifted off from pin e^2 . In the meantime this spring attempts to push 55 the lifting-piece from the position of rest, Fig. 1, to that shown in Fig. 2, so that the catching of tooth e into the teeth of both racks is secured. The construction and arrangement of the hour and of the quarter step-wheels is the usual one, except that the hour 60 step plate or wheel is fixed upon a solid pin h' . The lever s^2 must be wound up or pushed back against its spring until the lever b^1 abuts against the step-wheel h , Fig. 2, and until the lever b will be arrested and will keep this position during the further and complete movement of rack s . While the pin d , secured to 65 the lever b in the hole b^3 , turns with said lever and with the hour-rack lever s^2 , the pin or screw head c' , attached to the rack s , pushes back the check-lever d until its pawl d^3 lets free the quarter-rack v , kept by its nose v^5 . By the impulse of spring f the quarter-rack

springs forward until its arm v' strikes upon the step-wheel m , as shown in Fig. 2, and the said quarter-arm is ready to strike the second quarter or half hour. In executing this movement the teeth v^6 of the quarter-rack pass under the lever e , now set free, while the somewhat stronger spring f will overcome the effect of the weak spring e^3 . If the hook d^3 70 has set free the quarter-rack v or its nose v^5 , respectively, and the lever s^2 is let free, the striking mechanism will work; but if this lever is set free before the quarter-rack has been released—that is to say, before the 80 quarter-rack has been fully wound up—the striking cannot take place, as the curved arm v^4 of the quarter-rack has brought the tooth e out of gear with the teeth of the hour-rack. (See Fig. 1.) By means of the escapement 85 mechanism herein shown and described the repeating-works will act exactly or totally fail to act. In my invention the full hours are distinguished by single strokes and the quarters by double strokes following speedily one 90 upon the other.

The driving-gear of the strike-regulating mechanism is shown upon an enlarged scale in Fig. 7, Sheet 1, and the regulating mechanism is shown upon a still larger scale in 95 several figures of Sheet 2 of the drawings.

When the works are wound up by actuating the lever s^2 , the hour-rack gears with the pinion t , and in running down it engages the latter with the ratchet-wheel t' , fastened 100 thereon, and by the pawl T' , fixed upon the wheel z , the latter actuates the pinion z^2 , gear-wheel z' , pinion A' , and regulating mechanism shown by the figures on Sheet 2 of the drawings, which is located over the time- 105 movement—that is to say, on the opposite side of the plan view shown in Fig. 7—and the axis of said mechanism may be held by a bridge secured to the plate. In these figures two small disks A and B , similar to one another, each have two segments connected by diametric cross-pieces and resemble two mutilated disks having oppositely-disposed rectangular recesses. The lower disk A is solidly connected with the pinion A' and is engaged by the repeating-work, as above described. The disk A is provided with two opposite slits A^2 , directed from the periphery to the interior. The upper disk B is put loosely upon the arbor C and is provided with 110 slits B' , which cross the slits A^2 of disk A . Where the disks cover one another the slits A^2 and B' form in their projection a square hole D , which moves inwardly or outwardly, according to the changing positions of the 115 disks as they move upon each other, Fig. 10 showing the extreme outer, position of the hole D or crossing-point of the two slits. The adjustment of the disks one upon the other is effected 120 by a screw E upon disk A , having an eccentric head E' , which fits the slot B^2 in plate B and which will displace the latter if turned 125 and hold it in the position which it should

have with relation to the disk A to bring the cross-hole D nearer to or farther from the periphery of the disk. The cross-hole D provides a bearing for the pivot-pin F², connecting the flies F' of the brake F, formed by segment-plates fastened to a center block, as shown in Figs. 12 and 13. The ends or flies F' form fork projections which extend over the disks A and B and project beyond them and are thrown out eccentrically to said disks to a greater or less degree, governed by the position of the pin F² in the cross-slots, by the revolution of the whole regulating mechanism in the direction of the arrow. If only the lower disk A should be provided, as shown in Fig. 14, the pin F² will be pushed outwardly by the oblique position of the slit A², and the part of the fly-brake F near by the pin would be pressed against the brake-ring, as shown in Fig. 14, so that the part of the fly-brake endeavoring to move outwardly from its center by the effect of centrifugal force will work as a very long lever and will therefore produce a very strong brake. Moreover, if the disk B is placed upon disk A in such a position that the pins F² will sit toward the center and a revolution takes place a minimum breaking power will be effected. Between these two extremes a great latitude of adjustment of the brake-power may be effected, and this may be accurately adjusted by means of the eccentric head upon the regulating-screw E.

The regulation of the speed of the hammer or of the repeating mechanism is by this means not dependent upon delicate springs, as heretofore, which must be nicely adjusted for the connection of defects, while a positive and exact adjustment of the brake may be effected by a set-screw and by simple and effective means, which will insure perfect and constant regulation of the speed.

By means of my improved striking mechanism the number of parts is reduced to the least number practicable, and both the full-hour and the quarter-hour strokes are struck distinctly upon a single annular sounding ring by a single hammer.

The hammer is lifted sufficiently to effect an energetic stroke, and the sound of each hour and quarter-hour is made clear and distinct, and each quarter-hour by my improved construction of quarter-hour sector-teeth, arranged in pairs, clearly distinguish the

strokes of the quarter-hour from the strokes 55 of the hour-signal.

The centrifugal regulator herein described differs materially from any devices heretofore employed, as the plates which control the fly-brake are placed one upon the other and 60 work noiselessly without the employment of springs, thus securing a simple, strong, and compact construction and arrangement of parts.

I claim as my invention and desire to secure by Letters Patent—

1. In a repeater for watches, the combination of the hammer mechanism, the hour rack and lever, a double-armed lever pivoted thereto to have a limited oscillating movement thereon, an hour-cam to engage said lever, a check-lever pivoted to said double-armed lever and a quarter-hour check-lever to be engaged by the said check-lever, substantially as described. 75

2. A repeater for watches comprising a hammer and hammer-actuating lever, a step-wheel h, an hour rack and lever, a step-wheel m, a quarter-hour rack and lever having a curved arm v⁴, projecting from the heel end 80 of the said rack, a nose v⁵ and an arm v' branching from the short end of said lever, and a check-lever d, substantially as described.

3. In a repeating-watch regulator for the speed of the striking mechanism, comprising two oppositely-disposed plates, pivoted together and having cross-slots in the rims thereof, and a fly-brake provided with a pivot supported in said cross-slots, substantially as 90 described.

4. In a repeating-watch, a regulator for the speed of the striking mechanism, comprising two oppositely-disposed plates, pivoted together and having cross-slots in the rims 95 thereof, a fly-brake provided with a pivot supported in said cross-slots, and an adjusting-screw to hold the pivot-supporting plates in proper position to regulate the fly-brake, substantially as described. 100

In testimony that I claim the foregoing as my invention I have signed my name in presence of two subscribing witnesses.

CARL HAHLWEG.
